CLAIM

The ornamental design for an injection device, substantially as shown and described.

DESCRIPTION

FIG. 1 is a perspective view of the ornamental design for an injection device;

FIG. 2 is a side view of a first side of the ornamental design of FIG. 1, of which the opposite side is a mirror image;

FIG. 3 is a side view of a second side of the ornamental design of FIG. 1;

FIG. 4 is a side view of a third side of the ornamental design of FIG. 1;

FIG. 5 is an end view of a first end of the ornamental design of FIG. 1; and,

FIG. 6 is an end view of a second end of the ornamental design of FIG. 1.

The broken lines depict portions of the injection device that form no part of the design.

1 Claim, 5 Drawing Sheets
